APPARATUS FOR MANUFACTURING INNER TUBES

Ross Patrick, Indianapolis, Ind., assignor, by
nunc prossne assignments, to United States Rubber
Company, New York, N. Y., a corporation of
New Jersey

Application September 10, 1936, Serial No. 100,136

1 Claim. (Cl. 154—9)

This invention relates to the manufacture of inner tubes, and in particular it relates to a method and means for providing an aperture in an inner tube in alignment with a valve stem.

5 The adoption of the rubber type of valve stem requires new and different means of treating inner tubes, particularly in respect to the assembly of rubber valve stems. Rubber valve stems have a flexible rubber base which is vulcanized directly to the inner tube. Previously it has been customary to assemble the valve stem with the inner tube after the inner tube is in an advanced state of processing.

10 When an inner tube is extruded from a tubing machine it is customary to inject a lubricating material, such as soapstone powder, into the interior of the tube. This prevents the walls of the tube from adhering together. It is also customary to coat the outer surface of the inner tube with a soapstone powder.

15 In the application of a rubber valve stem to an inner tube it is highly desirable that the adjoining surfaces of the tube and the valve stem base be free from the presence of lubricating material. It has been general practice to lay a thin sheet of material on top of the inner tube at a location where the valve stem is to be subsequently applied. This sheet of material is placed on the tube before its exterior walls are 20 lubricated with a soapstone powder. Directly before the valve stem is applied to the tube the thin sheet of protective material is removed from the tube, a hole punched in the tube, and the valve stem applied to the tube in alignment 25 with the punched hole. This operation is objectionable in that, when the hole is punched through the wall of the tube it frequently occurs that a small quantity of the lubricating material issues from the interior of the tube and settles 30 on the outer wall of the tube surrounding the punched hole. As a result of the presence of such lubricating material, proper adhesion of the tube and valve stem through vulcanization cannot be obtained, and leakage takes place while 35 the tube is in operation.

40 My invention contemplates the application of a rubber valve stem to an inner tube prior to dusting the exterior walls of the tube with a lubricating material. A hole through the wall 45 of the tube in alignment with the valve stem is provided after the valve stem is assembled with the tube. It is, therefore, an object of my invention to form a valve stem hole through the wall of an inner tube after the valve stem is assembled with the inner tube.

Another object is to assemble the valve stem with the inner tube prior to the dusting of the exterior tube walls with a lubricating material.

A further object is to dispose of the material which is removed to form the valve stem hole 5

A still further object is to expedite the manufacture of inner tubes and to obtain economy thereby.

These and other objects and advantages appear more fully in the following detailed description, when considered in connection with the accompanying drawings, in which:

Fig. 1 is a side view, partly in section, of a portion of an embodiment of my invention; 15

Fig. 2 is an end view, in section, taken along section line II—II of Fig. 1;

Fig. 3 is a detailed view, in section, of means for guiding a valve stem into relative position with a cutting means; 20

Fig. 4 is a side elevational view of a complete embodiment of the invention;

Fig. 5 is an end elevational view, partly in section, the section being taken along section line V—V of Fig. 1; and 25

Fig. 6 is a side elevational view, partly in section of a portion of the embodiment of the invention, illustrating a method of inspection.

Referring to the drawings, and in particular to Figs. 1, 2, and 4, I illustrate an embodiment 30 of my invention comprising a pedestal 1 for supporting a bracket 2 and an arm 3. At the upper part of the arm 3, and near the extremity thereof, is a recess 4 into which a plate 5 is positioned with its top surface normally on an even plane 35 with the top of the arm 3 so as to keep the inner tube from engaging a cutting tool as the tube is mounted and withdrawn. The plate 5 is supported by pins 6 attached thereto and slideable in apertures 7 within the body of the arm 3. 40 A spring 8 normally maintains this plate 5 in its proper position relative to the arm 3.

A cutter tool 9 in tubular form is disposed below the top of the plate 5 and is secured to the arm 3. A heating element 10 circumscribes the 45 cutter tool 9 and functions to elevate the temperature of the cutter tool, thereby assisting in the cutting operation. An aperture 11 extending through the plate 5 permits the plate to be moved in a manner allowing the cutting tool 9 50 to extend therethrough.

The cutting tool 9 is provided with a tapered aperture 12 for facilitating the removal of the material cut from an inner tube. The aperture 12 connects with a pipe line 13 extending to a 55

6 tank or chamber 14. A pipe line 13 also connects with the tank 14 and communicates with a source of reduced pressure. The bottom of the tank 14 has a removable base 16 through which accumulations 10 of cut rubber plugs within the tank 14 may be removed. Pipe line 13 includes a valve 17 which is actuated during the operation of the apparatus.

10 In Fig. 2 an inner tube 18 and a valve stem 19 secured to the inner tube are shown in relative position with the apparatus in cutting position; that is, the plate 5 is forced downward, thus permitting the cutting tool 9 to extend through the plate 5 and through the wall of the tube 18.

15 The tubular cutter 8 forms an aperture through the wall of the tube 18, the material remaining therefrom being in the form of a plug or disc 20. This plug 20 is removed due to the reduced air pressure within the tubular cutter 8. Thereafter the plug is carried through the pipe 20 line and deposited within the tank 14.

20 In order to locate the valve stem 19 and to force the stem downward toward the cutter tool, I provide a tubular guide member 21 adapted for vertical reciprocating movement. The tubular member 21 is slidably supported within a bushing 22 held by an arm 23 extending from the bracket 2.

25 As shown in Fig. 3, a portion of the tubular member 22 is provided with rack teeth 24 for complementary association with a gear 25. A shaft 26 keyed to the gear 25 also carries an arm 27 to which a connecting link 28 is pivotally secured. The opposite end of the link 28, as shown in Fig. 5, is pivotally attached to a foot pedal 29 extending from the side of the pedestal 1. A spring 30 normally maintains the foot pedal 29 in such manner that the tubular member 21 is in upward position, as shown in Fig. 1.

30 A branch connecting link 31 is pivotally attached to the connecting link 28 at 32, and its opposite end connects with a lever 33 for operating the valve 17. The branch connecting link 31 attaches to the lever 33 through a slot 34 at the upper part of the connecting link 31. The purpose of the slot 34 is to permit a variation between the operation of the valve 17 and the vertical movement of the tubular member 21. This variation is desirable in that vacuum is applied after 35 the tubular member begins its downward movement, and the vacuum is continued until the tubular member 21 approaches the limit of its upward movement.

35 An electric light 35 positioned near the extremity of the arm 3 lies in the path of the tube 18 as it is removed from the arm 3, thus enabling an operator to inspect the tube as it is with-

drawn from the arm to insure that the plug 20 has been properly removed from the tube. This method of inspection is illustrated in Fig. 6.

40 In the operation of the apparatus, an operator places the end of a tube carrying a valve stem 5 over the arm 3. It is to be understood that this operation takes place during the manufacture of the inner tube, and prior to the splicing of the ends of the tube to form a tubular annulus. The end of the valve stem 19 is manually guided into 10 the aperture of the tubular member 21. Thereafter the operator presses the foot pedal 29, thus actuating the gear 25 and moving the tubular member 21 downward. The tubular member 21 engages with the base of the valve stem 19 and 15 forces same downward to depress the spring 30. As a result of this movement, the plate 5 is moved downward, and the cutting tool 8 extends through the plate 5 a distance equal to at least the thickness of the inner tube wall. 20

25 The heating element 10 is in continuous operation, and therefore the knife edge of the cutting tool 8, assisted by the elevated temperature, easily cuts a circular aperture through the wall of the tube 18.

30 Simultaneously with the downward movement of the tubular member 21, the valve 17 is actuated, resulting in a reduced pressure at the under side of the plug 20. As soon as the wall of the tube 18 is completely severed, the plug 20 is carried by the moving air through the pipe connection 13 and into the tank 14.

35 When the operator releases the pedal 29 the spring 30 returns the mechanism to its normal position and the valve 17 is closed. Thereafter the operator slides the tube off the arm 3, and as it passes the electric light 35 the operator's line of vision extends through the aperture of the valve stem, and it is readily ascertained if the plug 20 is entirely removed from the wall of 40 the inner tube.

45 While I have shown certain preferred embodiments of my invention, it will be understood that modifications may be made therein without departing from the spirit of the invention and the 45 scope of the appended claim.

Having thus described my invention, what I claim and desire to protect by Letters Patent is:

50 Apparatus for manipulating inner tubes comprising a support insertable into an open end of an inner tube having a hole in a wall for co-operation with an attached valve stem, and means carried by the support for illuminating the hole and the interior of the valve stem as the tube is withdrawn from the support. 55

ROSS PATRICK.
